[57] CLAIM

The ornamental design for a motorcycle taillight cover, as shown and described.

DESCRIPTION

FIG. 1 is a perspective view as seen from the front, top and side of a motorcycle taillight cover;

FIG. 2 is a front elevation view thereof;

FIG. 3 is a rear elevation view thereof;

FIG. 4 is a bottom plan view thereof;

FIG. 5 is a side elevation view thereof;

FIG. 6 is a top plan view thereof; and,

FIG. 7 is a side elevation view thereof, from a side opposite that of FIG. 5.
